UNITED STATES PATENT OFFICE.

JOHN W. NEWBERRY, JOSIAH M. REED, AND MARTIN THEODORE KUHLKIN,
OF NEW YORK, N. Y., ASSIGNEES, BY DIRECT AND MESNE ASSIGNMENTS,
TO MONARCH COATED PAPER COMPANY, EXISTING UNDER THE LAWS
OF MAINE.

MACHINE FOR MARBLING PAPER.

No. 852,503.

Specification of Letters Patent.

Patented June 25, 1907.

Application filed November 2, 1905. Serial No. 285,539.

To all whom it may concern:

Be it known that we, JOHN W. NEWBERRY, 5
JOSIAH M. REED, and MARTIN THEODORE
KUHLKIN, citizens of the United States, and
residents of the city of New York, in the
counties of Kings and New York and State
of New York, have invented certain new and
useful Improvements in Machines for Mar-
bling Paper, of which the following is a
specification.

This invention relates to a device which
is embodied in a machine for marbling paper,
the object being to provide a machine which
shall produce the best results in the most
efficient manner and which shall require
very little attention in its operation. To
accomplish this result we provide a circular
tank mounted upon suitable standards,
which tank is adapted to contain a sizing so-
lution. Above this tank is mounted a car-
riage which is adapted to be rotated in a
path corresponding to the circle of the tank.
This carriage is designed to hold the roll of
paper to be marbleized and carries a mech-
anism for unrolling said paper and bringing
successive portions of the same into contact
with the sizing solution as the carriage is re-
volved. Provision is also made for carrying
the paper after it has been brought into con-
tact with the sizing solution as described
over a drying chamber forming a part of said
carriage and from thence to a roll where it is
finally rewound.

Rotating brushes for distributing the col-
oring solutions are mounted upon a suitable
frame immediately in advance of the carriage
carrying the paper. These brushes operate
in conjunction with a distributing roll and
operate to distribute the colors upon the
surface of the sizing solution in advance of
the paper as will be more fully described
hereinafter.

The circular tank above referred to is par-
tially filled with a solution of gelatinous
material which forms the sizing or gum so-
lution and is of such a consistency as to
form a cushion upon which the various colors
which it is desired to transfer to the surface
of the paper may be distributed. This siz-
ing is composed of a solution of slippery elm,
flaxseed, and gum-tragacanth, which has
been found to give the best results for this
purpose. The coloring material consists

of earth colors, such as are usually employed
for this purpose, and are so arranged as to 55
be distributed over the surface of the sizing
solution immediately in advance of the paper
by means of the rotating brushes and rollers
heretofore mentioned.

In the accompanying drawings we have 60
illustrated our invention as applied to a ma-
chine for the purpose set forth and in the
description of this machine the various novel
features of our invention will be more fully
set out in connection with the several parts 65
of the mechanism.

Figure 1 is a sectional side elevation of a
machine such as described illustrating the
circular tank and the carriage and distribut-
ing brushes adapted to be revolved over said 70
tank by means of a vertical central driving
shaft, as shown. The section is taken on
the line X—X of Fig. 2. Fig. 2 is a top plan
view of Fig. 1 and illustrates the relative lo-
cation of the carriage and distributing 75
brushes. Fig. 3 is an enlarged side elevation
of a portion of Fig. 1 illustrating the carriage
in position above the circular tank. Fig. 4
is a detailed perspective view of a roll and
scraper which is designed to remove the ex-
cess gum from the paper. Fig. 5 is an en-
larged end elevation of the carriage, par-
tially in section, on the line Y—Y, looking in
the direction of the arrows, in Fig. 2. Fig. 6
is an enlarged top plan view of a distributing 80
brush and roll mounted upon their frame-
work over the circular tank. Fig. 7 is a sec-
tional end view on the line Z—Z, looking in
the direction of the arrows, of Fig. 6. Fig. 8
is an end elevation of the driving gears which 85
rotate the brush and roll shown in Fig. 6.
Fig. 9 is a detailed view of a distributing
brush.

The operation of the machine is as follows:
A roll of blank paper 1 being placed in posi- 95
tion as shown in Figs. 1 and 3, the paper is
fed from this roll, as indicated by the arrows
in Fig. 3, over the guide rolls 2 and 3 to the
driving roll 4, from whence it passes under
the contact roll 5 into contact with the colors 100
which are distributed over the surface of the
sizing solution in the circular tank. The
carriage carrying the paper is revolved over
this circular tank by means of the central ver-
tical shaft 6, which is driven by the pulley 105
and belt 7. At the lower end of this shaft is

provided a pair of beveled gears which transmit the movement thereof to the horizontal shaft 8 which has a spur gear 9 secured thereto and which meshes with a fixed circular rack 10. The outer end of the shaft 8 is held in suitable bearings secured to the carriage and also has the driving roll 4 secured thereto. The driving mechanism is so designed that the carriage will be revolved over the circular tank at the same speed as that of the paper which is unrolled as described and consequently there will be no relative horizontal movement between the sizing and the paper at the point under the roll 5 where they are brought into contact. This roll 5 is mounted upon a hand lever 11 by means of which the paper can be brought into position so as to come into contact with and take up the colors which have been deposited upon the surface of the sizing by the distributing brushes. From this point the paper passes under a pressure roll 12 having a fixed scraper 12', which is designated as a doctor, over a scraper roll 13 and under a pressure roll 13', as shown in Figs. 3 and 4. These two latter rolls operate to remove any surplus gum or sizing solution from the paper. From these rolls the paper passes under a guide roll 14 and under a preliminary drying chamber 56 which is heated by gas jets from pipe 57, over the drum 15 which is heated, to the drying chamber 16, which is heated by means of a series of gas jets 17, or other suitable means, and from which it passes over the drum 18, which is also heated, and guide rolls 19, 20 and 21 to the roll 22 upon which it is rewound. The rewinding roll 22 is driven by means of a belt 23 from a pulley mounted upon the end of the driving shaft 8. A tension roller 24, which is regulated by means of a strap 25 and weights 26, controls the rotation of the rewinding roll.

The purpose of the pressure roll 12, the doctor 12', the scraper roll 13 and the pressure roll 13', shown in Figs. 3 and 4, is to remove any of the sizing solution which may have been picked up by the paper in passing under the roll 5 without disturbing the colors which are taken up by the paper at this point. A pivoted bracket 27 carries the scraper or doctor 12' which takes any excess gum from the upper surface of the paper and also carries a pressure roll 12 which rests upon the upper surface of the paper and brings the under surface into contact with the scraper roll 13 which is mounted upon a fixed support. This is designated as a scraper roll on account of its construction, shown more clearly in Fig. 4. This roll 13 traveling at a somewhat greater speed than the paper removes the surplus gum from the surface as described. A scraper 28 is provided which in turn scrapes the gum solution from the roll and allows it to drip into pan 29, from which it flows through a trough 30

to a circular receptacle 31. From this receptacle it is drawn off by means of a pipe 32.

An overhead tank may be provided in any suitable location into which the surplus gum collected from the pipe 32 may be pumped by any suitable pumping device. A feed pipe may be provided leading from this tank to supply the gum solution to the large circular tank. Such a pipe is shown at 33 in Fig. 2 having branches therefrom passing underneath the aforesaid large circular tank and provided with inlet valves to control the flow of the gum solution to one or more points in the said circular tank. These pipes are shown at 34, 35 and 36 in Fig. 3, and the controlling valves 37 and 38 are likewise shown in Fig. 3. The arrangement of these various supply pipes and valves is also shown in Fig. 1 and 2.

The revolving carriage is moved around above the circular tank by means of the driving gear 9 and circular rack 10, as has been described. The carriage is supported on the outside by means of a roller 39 resting upon a circular track 40. A chain 41 is driven by a sprocket wheel mounted upon the driving shaft 8, as shown in Fig. 5. This chain also drives the scraping roll 13 and the drum 15, as shown in Fig. 3. The size of these sprockets is so arranged that the circumference of the several rolls driven thereby will move at the same speed as the paper which is passing over the same, except the scraping roll 13 which rotates slightly faster than the paper web passing over the same in order to remove the adhering gum, as described above.

One of the important features of my invention is in the construction and arrangement of the distributing brush and roll, which is shown in detail in Figs. 6, 7, 8 and 9. The brush is composed of a central spindle 42 mounted upon a shaft 43 having a gear 44 attached to one end thereof. This gear is driven through an idle gear 45, mounted upon a suitable bearing secured to the brush carriage 46, and which in turn is driven from the circular rack 10 as the brush carriage is moved ahead in the direction indicated by the arrow at the lower part of Fig. 6. This will rotate the brush in the direction indicated by the arrow over the same in Figs. 7 and 8.

The distributing roll 47 is mounted upon a shaft 48, supported in suitable bearings on the carriage 46. A driving gear 49, secured to the end of the shaft 48, meshes with and is driven with the idle gear 45 in the direction indicated by the arrow in Figs. 7 and 8.

The colors may be supplied to the distributing roll from a suitable receptacle, such as a pail shown at 50 in Fig. 1, and are allowed to flow into the drip pan 51, as shown in Fig. 7, extending under the distributing roll 47 which bears a roller or idler in the bottom of the pan 47', which agitates the color. From

this pan the colors are carried up by the roll 47 and supplied to the brush continuously. It will be noted that the brush and roll rotate in the opposite directions at the point where 5 the former touches the latter. A wire 52 is adjustably located slightly below the point where the brush in its rotation wipes off or takes up the color from the roll. The function and purpose of this wire is to cause the 10 bristles of the brush to snap off from the same and so scatter and distribute the color which has just been taken up by these brushes over the surface of the gum solution in the large circular tank over which the 15 brush is traveling. By using brushes having bristles of different degrees of stiffness and also by varying the arrangement of the bristles the colors will be distributed with a different velocity and consequently in different 20 arrangements and designs over the surface of the gum solution.

A secondary drip pan 53 is provided to catch any overflow or drippings from the pan 25 51 and so prevent the same from falling upon the surface of the gum solution underneath. Any number of these color distributing carriages may be used according to the number of different colors necessary in the design to be transferred to the paper. These several 30 carriages are connected to the main carriage carrying the paper directly in advance of the same and are connected together by means of suitable links, such as 54. The color distributing carriages are mounted upon suitable 35 wheels 55 adapted to be revolved around the circular track 40 in connection with and in advance of the main carriage, as already described.

The construction as herein shown and 40 described embodying a circular tank containing the gum solution and a carriage carrying the paper and adapted to be revolved over said tank, presents many advantages which will be self-evident. The circular movement permits of a continuous operation of the machine in the supplying of the colors to the gum solution and in the taking up of these colors continuously by the paper. By providing a drying chamber through which 45 the paper is passed provision is made for a continuous operation of the machine by drying the colors on the paper and then rewinding the paper without removing it from the machine.

50 The construction as shown and described of the distributing roll and brush presents several features which have been found in practice to give the best results. By so locating and rotating the brush and roll that 55 the brush takes the color from the roll as it is traveling downward and from which it is immediately snapped off by means of the wire much better results are obtained than by dipping the brush directly into the color solution or by carrying the same on the

brush over the top of its circumference before distributing it to the gum solution. By varying the size of the driving gears the speed of the brush or roll may be regulated to give the distributing effect desired to the 70 colors.

The device herein shown and described illustrates an embodiment of our invention in a practical machine for the purpose set forth which we have found after numerous 75 experiments to give the best results. We do not confine ourselves, however, to the exact details of construction or to the design and arrangement of the several parts of the machine herein shown and described, as it will 80 be evident that various changes may be made therein without departing from the scope of our invention.

What I claim is:

1. In a marbling machine, the combination of a tank adapted to contain a sizing solution, a carriage adapted to carry the paper to be marbleized, a drying chamber, means for distributing coloring matter over said solution, and means for passing the 90 paper successively into contact with the color film carried by said sizing solution and through said drying chamber.

2. In a marbling machine, the combination of a circular tank adapted to contain a 95 sizing solution, a revolving carriage carrying the paper to be marbleized and having a drying chamber in connection therewith, a rotating brush adapted to be revolved in advance of said carriage, and means for passing 100 the paper successively into contact with the color film carried by said sizing solution and through said drying chamber, substantially as described.

3. In a marbling machine, the combination of a circular tank adapted to contain a 105 sizing solution, means for maintaining a constant amount of said sizing solution in said tank, a revolving carriage adapted to carry the paper to be marbleized, means for distributing coloring matter over said solution, and means for passing the paper successively into contact with the color film carried by said solution.

4. In a marbling machine, the combination of a circular tank adapted to contain a sizing solution, a reservoir adapted to contain surplus solution, a pumping device adapted to transfer said solution to said reservoir, a supply pipe leading from said reservoir for maintaining a constant amount of said sizing solution in said tank, a revolving carriage carrying the paper to be marbleized, a rotating brush adapted to be revolved in advance of said carriage, and means for passing the paper successively into contact with the color film carried by said sizing solution, substantially as described.

5. In a marbling machine, the combination of a circular tank adapted to contain a 130

sizing solution, a reservoir adapted to contain surplus solution, a pumping device adapted to transfer said solution to said reservoir, a plurality of supply pipes leading 5 from said reservoir for maintaining a constant amount of said sizing solution in said tank, a revolving carriage carrying the paper to be marbleized, a rotating brush adapted to be revolved in advance of said carriage, 10 and means for passing the paper successively into contact with the color film carried by said sizing solution, substantially as described.

6. In a marbling machine, the combination 15 of a tank adapted to contain a sizing solution, a rotating brush, a supply roll operating in conjunction with said brush to distribute coloring matter over the surface of said sizing solution, and means for passing 20 the paper successively into contact with the color film carried by said sizing solution, substantially as described.

7. In a marbling machine, the combination 25 of a tank adapted to contain a sizing solution, a plurality of rotating brushes, a plurality of supply rolls operating in conjunction with said brushes to distribute coloring matter over the surface of said sizing solution, and means for passing the paper successively 30 into contact with the color film carried by said sizing solution, substantially as described.

8. In a marbling machine, the combination 35 of a circular tank adapted to contain a sizing solution, a revolving carriage carrying the paper to be marbleized, a rotating brush and roll adapted to be revolved in advance of said carriage, means for supplying coloring material to said brush and roll, and means 40 for passing the paper successively into contact with the color film carried by said sizing solution, substantially as described.

9. In a marbling machine, the combination 45 of a circular tank adapted to contain a sizing solution, a revolving carriage carrying the paper to be marbleized, a brush and roll adapted to be revolved in advance of said carriage, means for supplying coloring material to said brush and roll, and means for 50 passing the paper successively into contact with the color film carried by said sizing solution, substantially as described.

10. In a marbling machine, the combination 55 of a circular tank adapted to contain a sizing solution, a revolving carriage carrying the paper to be marbleized, a series of color distributing devices each comprising a rotat- 60 ing roll and brush adapted to be revolved in advance of said carriage and means for passing the paper successively into contact with the color film carried by said sizing solution, substantially as described.

11. In a marbling machine, the combination 65 of a tank adapted to contain a sizing solution, a rotating brush, a supply roll oper-

ating in conjunction with said brush to distribute coloring matter over the surface of said sizing solution, a supply receptacle containing coloring matter located in proximity to said supply roll, a drip pan located under 70 said supply receptacle, and means for passing the paper successively into contact with the color film carried by said sizing solution, substantially as described.

12. In a marbling machine, the combination 75 of a circular tank adapted to contain a sizing solution, a rotating brush and roll driven by means of a rack and gear, a circular rack by means of which said brush and roll are rotated, means for revolving said 80 brush and roll over said rack and tank, means for supplying coloring material to said brush and roll, and means for passing the paper successively into contact with the color film carried by said sizing solution, substan- 85 tially as described.

13. In a marbling machine, the combination 90 of a circular tank adapted to contain a sizing solution, a revolving carriage carrying the paper to be marbleized, a scraper roll 95 adapted to remove the adhering sizing solution from the paper, and means for passing the paper successively into contact with the color film carried by said sizing solution and said roll, substantially as described. 95

14. In a marbling machine, the combination 100 of a circular tank adapted to contain a sizing solution, a rotating brush and roll driven by means of a rack and gear, a roll adapted to be revolved by the aforesaid roll 105 to agitate the color solution, a circular rack by means of which said brush and roll are rotated, means for revolving said brush and roll over said rack and tank, means for supplying coloring material to said brush and 110 roll, and means for passing the paper successively into contact with the color film carried by said sizing solution, substantially as described.

15. In a marbling machine, the combination 110 of a circular tank adapted to contain a sizing solution, a revolving carriage carrying the paper to be marbleized, a scraper roll, a 115 scraper, a pressure roll co-operating with said scraper roll and scraper to remove the adhering sizing solution from the paper, and means for passing the paper successively into contact with the color film carried by said sizing solution and said roll and scraper, substantially as described. 120

16. A machine for marbling paper provided with a tank or vessel, a rotatable frame mounted thereover, a support mounted on said rotatable frame and open at the bottom, a roller mounted in said support, means for supplying coloring material to said roller and a brush operating in connection with said roller and adapted to discharge the coloring material into the tank. 125

17. A machine for marbling paper pro- 130

vided with a tank or vessel, a rotatable frame mounted thereover, a support mounted on said rotatable frame and open at the bottom, a roller mounted in said support, means for supplying coloring material to said roller and a brush operating in connection with said roller and adapted to discharge the coloring material into the tank, said rotatable frame being also provided rearwardly of said support with means for drawing paper through the top portion of the tank.

18. In a machine for marbling paper, an annular tank, a rotatable frame mounted thereover, a roller mounted over said rotatable frame, a brush mounted forwardly of and operating in connection with said roller, and means for supplying coloring material to said roller.

19. In a machine for marbling paper, an annular tank, a rotatable frame mounted thereover, a roller mounted over said rotatable frame, a brush mounted forwardly of and operating in connection with said roller, and means for supplying coloring material to said roller, said rotatable frame being also provided rearwardly of said roller with a supplemental frame, paper rollers mounted therein, and means for drawing paper from one of said rollers onto another and for passing it through the top portion of the tank.

20. In a machine of the class described, an annular tank, a rotatable frame mounted thereover, a support mounted on said rotatable frame and open at the bottom, a roller mounted in said support and turnable in a receiver, means for discharging coloring material into said receiver; a brush mounted in front of said roller and operating in connection therewith and designed to remove the material therefrom and deposit it in said tank.

21. In a machine of the class described, a main frame, an annular tank mounted therein, an annular gear mounted concentrically within said annular tank and provided with upwardly directed teeth, a rota-

table frame mounted over the main frame, a roller mounted over the main frame, means for supplying coloring material to said roller, and a brush mounted in front of said roller, said roller and said brush being geared in connection with said annular gear.

22. In a marbling machine, the combination of a tank adapted to contain a sizing solution, a carriage traveling over said tank, a rotating brush mounted on said carriage, a stop adapted to retard the rotation of the outer ends of the bristles of said brush to distribute coloring matter over said sizing solution, and means for passing a strip of paper successively into contact with said coloring matter.

23. In a marbling machine, the combination of a tank adapted to contain a sizing solution, a carriage traveling over said tank, a rotating brush mounted on said carriage, an adjustable stop adapted to retard the rotation of the outer ends of the bristles of said brush to distribute coloring matter over said sizing solution, and means for passing a strip of paper successively into contact with said coloring matter.

24. In a marbling machine, the combination of a tank adapted to contain a sizing solution, a carriage traveling over said tank, a rotating brush mounted on said carriage, a wire interposed in the path of the outer ends of the bristles of said brush to retard the rotation of the same to distribute coloring matter over said sizing solution, and means for passing a strip of paper successively into contact with said coloring matter.

Signed at New York city, in the county of New York and State of New York this 20th day of Oct. A. D. 1905.
